UNITED STATES PATENT OFFICE

135,656

DESIGN FOR A TIE RACK

William Grant Williams, Anaheim, Calif.

Application February 6, 1943, Serial No. 109,480

Term of patent 7 years

To all whom it may concern:

Be it known that I, William Grant Williams, a citizen of the United States, residing at Anaheim, in the county of Orange and State of California, have invented a new, original, and ornamental Design for a Tie Rack, of which the following is a specification, reference being had to the accompanying drawing, forming part thereof.

Figure 1 is a view in side elevation of the tie rack embodying my new design, illustrating the tie rack in its collapsed or retracted position;

Fig. 2 is a view in front elevation of the tie rack in the position shown in Fig. 1;

Fig. 3 is a view in side elevation illustrating the tie rack in extended position; and

Fig. 4 is a view in vertical section taken substantially upon the line 4—4 of Fig. 3 in the direction indicated by the arrows.

I claim:

The ornamental design for a tie rack, as shown and described.

WILLIAM GRANT WILLIAMS.
